UNITED STATES PATENT OFFICE

GEORGE L. FULK, OF CLEVELAND, OHIO, ASSIGNOR, BY MESNE ASSIGNMENTS, TO BONNAR-VAWTER FANFORM COMPANY, INC., OF CLEVELAND, OHIO, A CORPORATION OF DELAWARE

PRINTING PRESS

Application filed April 13, 1926. Serial No. 101,633.

The present invention relates to printing presses of the cylinder type and has for its object to provide means by which the time in which the press must remain idle while being made ready for a new job is greatly reduced.

More specifically, it is the object of the present invention to provide a printing press in which the pairs of co-acting printing cylinders are mounted for removal as a unit from the press so that when one run is completed the cylinder unit or units may be removed bodily and replaced by other cylinder units which have been made ready for the next printing operation.

15 The invention further provides means for facilitating the changing of plates on the printing cylinders and for adjusting the pressure of the co-acting cylinders of units which have been removed from the press so that the detached cylinder units may be made ready for a new job while the press is operating.

With the above and other objects in view the invention may be said to comprise the 25 device as illustrated in the accompanying drawings hereinafter described and particularly set forth in the appended claims together with such variations and modifications thereof as will be apparent to one skilled in the art to which the invention appertains.

Reference should be had to the accompanying drawings forming a part of this specification, in which:

25 Fig. 1 is a plan view showing a printing press, a plurality of make-ready stands and the crane for transferring the cylinder units from the press to the make-ready stands and from the stands to the press.

40 Fig. 2 is a side elevation of the printing press.

Fig. 3 is a side elevation of the press looking toward the side opposite that shown in 45 Fig. 2.

Fig. 4 is a plan view of one of the make-ready stands showing a cylinder unit in place thereon.

Fig. 5 is a side elevation of the make-ready 50 stand.

Fig. 6 is an end elevation of the make-ready stand.

Figs. 7 and 8 are detail views showing the detachable connection between the ends of the track rails on one side of the supporting 55 frame of the press and the supporting frame.

Fig. 9 is a side elevation of one of the supporting blocks in which the journals for the two co-acting cylinders of a printing unit are adjustably mounted.

Fig. 10 is a top plan view of the supporting block.

Fig. 11 is a side elevation showing a slightly modified form of press in which the inking mechanisms are carried by a movably mounted frame.

Figs. 12 and 13 are detail views showing in side elevation and in horizontal section, respectively, the detachable connection between the press frame and inking mechanism frame.

The opposite sides of the frame 1 of the printing press shown in Figs. 2 and 3 are provided with front, rear and intermediate standards 2, 3 and 4 and supported upon the upper ends of the front standards 2 are the 75 feed-out cylinders 5. The intermediate standards 4 support between them the printing cylinders which, as herein illustrated, are arranged in pairs one above the other between the standards 4. The standards 4 are 80 provided with horizontally disposed sockets 6 which are open toward the front end of the press and supporting rails 7 extend from the standards 4 to the front end of the frame, the supporting rails being located adjacent opposite sides of the frame at the level of the bottoms of the sockets 6. Removably mounted in each of the sockets 6 there is a cylinder supporting block 9, the supporting blocks 9 in horizontally aligned sockets on opposite 85 sides of the press frame supporting between them a pair of printing cylinders.

As best shown in Figs. 9 and 10 each supporting block consists of top and bottom plates 10 which are rigidly connected to end blocks 11 by means of screws 12. Between the end blocks 11 there are mounted two shaft journals 13. Midway between the ends of the block the top and bottom plates are connected on the outer side by a plate 14 which 100

serves to retain a wedge 5 between the two journals mounted in the block. The wedge 15 has one inclined side face and one of the journal sections has its inner face formed at the same inclination as the wedge. The 5 side plate 14 carries an adjusting screw 16 which bears against the outer end of the wedge and serves to adjust the wedge between the two shaft journals. One of the 10 end blocks 11 carries an adjusting screw 17 which may be turned to tightly clamp the adjacent journal against the wedge and to press the other journal against the opposite end block 11. By adjusting the wedge and 15 the screw 17 the pressure with which the cylinders are held in engagement may be varied. Of the two cylinders mounted between the blocks, one cylinder 18 is the plate cylinder which has its shaft 19 extending into one of 20 the journals 13 in each of the two supporting blocks and the other cylinder of the pair is a tympan cylinder 20 which has its shaft 21 extending into the other journal. The shafts 19 and 21 have fixed thereto at 25 one end intermeshing gears 22 and 23 so that one of the cylinders is driven from the other to feed the paper between the cylinders. One of the cylinder shafts 19 or 21 projects beyond the supporting block and has 30 fixed thereto a bevel gear 24 which is adapted when the supporting blocks are in place in the sockets 6 of the press frame to mesh with bevel gears 25 at the forward end of horizontal shafts 26. A driven shaft 26 is 35 provided for each of the superposed pairs of printing cylinders and these shafts carry bevel gears 27 at their rear end which are driven through bevel gears on a vertical shaft 28 on the rear standard 3. The shaft 40 28 may be driven by any suitable means and, in addition to driving the printing cylinders, drives the feed-out rollers 5 through a horizontal shaft 29 on the base of the frame 1 and a vertical shaft 30 on the front stand- 45 ard 2.

The printing press herein illustrated is a press designed for fanfold printing and has a series of printing cylinder units arranged one above the other, some of these 50 cylinder units being arranged to print upon one side of the paper and other units being arranged to print on the opposite side of the paper. If desired certain of the cylinder units may have plates on both cylinders so as to print on both sides of the paper, 55 in which case each cylinder will be both a tympan and a plate cylinder the plates being staggered on the two cylinders. The top cylinder unit in the press shown herein being 60 provided with two plate cylinders for this purpose.

Each of the printing cylinder units has an inking mechanism 31 connected to be 65 driven by the plate cylinder gear and adapted to deliver ink to the plate cylinder in a

manner well understood in the art. In order to permit the cylinder units to be readily removed from the press the inking mechanisms may be detachably connected to the cylinder supporting blocks by any suitable 70 means, attaching hooks 32 being shown herein for this purpose. The inking mechanisms of the cylinder units in which the plate cylinder is toward the front of the press are mounted upon the supporting rails 75 7 and when detached from the cylinder units these inking mechanisms can be pushed forwardly on the rails 7 into the space between the front standards 2 and when so positioned the cylinder units may be moved forwardly 80 out of the sockets 6 onto the rails 7 in position to be lifted and carried away from the press.

The inking mechanisms for the cylinder units having plate cylinders toward the rear 85 end of the press frame are mounted upon the supporting rails 33 which extend from the intermediate standards 4 to the rear standards 3. These inking mechanisms are also detachably connected to the cylinder 90 units so that the cylinder units can be released therefrom and removed from the frame. The paper is fed into the press through feed-in-rolls 34 mounted in the base of the press frame and passes between the 95 cylinders of the superposed units from the bottom to the top of the press and then forwardly to the feed-out rolls 5 from which the paper may be delivered to the folding mechanism. 100

For conveying the cylinder units from the press and for delivering cylinder units to the press a crane is provided which has a track 35 extending transversely across the top of the press directly over the supporting rails 7 and a hoist 36 which is mounted to travel on the track. The rails 7 at one side of the track are detachably connected to the standards 2 and 4 by means of the joint 37 shown in Fig. 7 so that they can be removed to permit passage of the traveling hoist in taking away a cylinder unit or bringing a cylinder unit to the press. The crane track 35 extends from the printing press over a series of make-ready stands 38 each of which is provided 115 with end standards 39 having flat tops adapted to receive the cylinder supporting blocks 9 so that a cylinder unit may be supported upon the top of the stand. Each of the end standards 39 is provided at one end with a 120 vertical abutment post 40 against which one end of the cylinder supporting block engages and each post 40 has hinged to the upper end thereof a hook 41 which is adapted to be 125 swung down upon the top of the cylinder supporting block resting on the top of the stand and engages the rear end of a block to hold the block in place on the stand. Each stand is provided with a transverse shaft 42 adjacent the top thereof and this shaft carries a 130

gear 43 which is so positioned that it will mesh with one of the gears on the cylinder shafts, and the shaft 42 has a crank handle 44 attached to one end by means of which the cylinders may be turned as may be required in detaching the old plates and replacing them with other plates. The cylinder units are so supported on the make-ready stands that the journal adjusting devices of the supporting blocks are readily accessible so that, after the plates have been attached to the plate cylinder the cylinders may be adjusted to obtain the proper pressure between the plate and tympan cylinders, and the stands may be provided with suitable inking rollers 45 so that impressions may be taken to show whether or not the cylinders are adjusted properly to obtain the best results.

After one run of the press has been completed, the cylinder units can be detached from the press frame and conveyed by the crane to the make-ready stands and other cylinder units which have been previously made ready for a new run may be conveyed to the press by the crane and be quickly put into place ready for operation so that the new run can be started on the press with very little delay. While the press is operating the cylinder units which have been previously removed can be made ready for a new run.

In Fig. 11 of the drawing there is shown a press which is identical with the press shown in Figs. 2 and 3 except that the supporting rails 7 are omitted and all of the inking mechanisms 31^a which are located in front of the cylinder units are mounted upon a supporting frame 46 mounted within the frame 1^a of the press on rollers 47 which travel on tracks 48 in the base of the frame 1^a, the frame 46 being movable from a position in which the mechanisms 31^a carried thereby are operatively engaged with the cylinder units to a position in which the frame 46 is between the front standards 2^a of the press frame and the space between the cylinder supporting standards 4^a and front standards 2^a is clear for the operation of the traveling hoist on the track 35^a so that the cylinder units can be readily removed and replaced by other cylinder units properly set up and adjusted for a new job.

For detachably securing the frame 46 to the standards 4^a, the standard at each side of the frame is provided with a keyhole slot 49 adapted to receive the flattened end 50 of a shaft 51 which is rotatably mounted in the side member of the frame 46. The shaft 51 has fixed thereto an arm 52 which normally hangs by gravity in a vertical position so that the flattened end 50 of the shaft is in a horizontal position and will pass into and out of the slot 49. To lock the frame 46 against movement the shaft 51 may be turned 20° to bring the flattened end 50 thereof to vertical

position within the enlarged portion of the slot 49, the arm 52 being secured in horizontal position by means of a locking pin 53 carried by the arm at its outer end and adapted to enter an opening in the frame 46 as shown 70 in Fig. 13.

Having thus described my invention, I claim:

1. A printing press having a supporting frame provided at opposite sides of the press with aligned sockets open at one side, a block 75 slidably mounted in each socket, and a pair of cylinders journaled at opposite ends in said blocks, said blocks and cylinders being removable from the press as a unit.

2. A printing press having a supporting frame provided at opposite sides of the press with aligned sockets open at one side, a block 80 slidably mounted in each socket, a pair of cylinders journaled at opposite ends in said blocks, said blocks and cylinders being removable from the press as a unit, and means for driving said cylinders including a gear carried by the supporting frame and a gear fixed to a cylinder and adapted to mesh with the gear on the frame when the cylinder unit is in place on the press.

3. A printing press having a pair of coacting printing cylinders mounted for removal 95 as a unit from the press, and means associated with the press for conveying the cylinder units to and from the press.

4. A printing press having printing cylinders arranged in pairs, each pair of cylinders 100 being removable as a unit from the press, and a conveying device associated with the press by which the cylinder units may be carried to and from the press.

5. A printing press having a supporting frame provided at opposite sides of the press 105 with aligned sockets open at one side, a block slidably mounted in each socket, and a pair of cylinders journaled at opposite ends in said blocks, said blocks and cylinders being removable from the press as a unit, said cylinders 110 being mounted for relative adjustment in said blocks.

6. A printing press having a supporting frame provided at opposite sides of the press with aligned sockets open at one side, a block 115 slidably mounted in each socket, a pair of cylinders journaled at opposite ends in said blocks and removable as a unit, and a crane having a track extending over said frame for 120 conveying cylinder units to and from the press.

7. A printing press having a supporting frame provided at opposite sides of the press with superposed sockets open at one side, the 125 sockets at one side of the press being horizontally aligned with sockets at the opposite sides, a block slidably mounted in each socket, a plate cylinder and a tympan cylinder journaled at opposite ends in horizontally aligned 130

blocks, the cylinders of each pair being relatively adjustable in the blocks and removable as a unit, and a crane having a track extending transversely across the press for conveying cylinder units to and from the press.

8. A printing press having a pair of coacting printing cylinders mounted for removal as a unit from the press, and an inking mechanism carried by the press and detachably connected to the cylinder unit.

9. A printing press having a supporting frame provided at opposite sides of the press with horizontally aligned sockets open at one side, a block slidably mounted in each socket,

15 a pair of printing cylinders journaled at their opposite ends in the blocks and an inking mechanism movably mounted on the frame and detachably connected to the blocks.

10. A printing press having a supporting frame provided at opposite sides of the press with horizontally aligned sockets open at one side, a block slidably mounted in each socket, a pair of printing cylinders journaled at their opposite ends in the blocks and removable as 25 a unit, an inking mechanism movably mounted on the frame and detachably connected to the unit and a crane having a track extending transversely over the frame for conveying the cylinder units to and from the press.

30 11. The combination of a printing press having a pair of printing cylinders mounted for removal as a unit therefrom, a make-ready stand adapted to receive the cylinder units, and means for conveying the cylinder units from the press to the make-ready stand and from the make-ready stand to the press.

12. The combination of a printing press having a pair of printing cylinders mounted for removal as a unit therefrom, a make-ready stand adapted to receive the cylinder units, means for conveying the cylinder units from the press to the make-ready stand and from the make-ready stand to the press, gearing carried by the cylinder unit through 45 which the cylinders may be driven, and gearing carried on the press and on the make-ready stand adapted to drive the gearing carried by the cylinder unit.

13. The combination of a printing press having a pair of printing cylinders mounted for removal as a unit therefrom, a make-ready stand adapted to receive the cylinder units, means for conveying the cylinder units from the press to the make-ready stand and from 55 the make-ready stand to the press, gearing carried by the cylinder unit through which the cylinders may be driven, driving means on the press adapted to be connected to the cylinders to drive the same, and manually operable means on the make-ready stand co-operating with said gearing for turning the cylinders.

14. The combination of a printing press having a pair of printing cylinders mounted 60 for removal as a unit therefrom, a make-

ready stand adapted to receive the cylinder units, and a crane for transferring cylinder units from the press to the make-ready stand and from the make-ready stand to the press.

15. The combination of a printing press having printing cylinders arranged in pairs, each pair being removable as a unit from the press, a plurality of make-ready stands each having means for supporting said cylinder units and for turning said cylinders, and a crane having a track extending over the press and over said stands for transferring said units from said press to said stands and vice versa.

16. The combination of a printing cylinder unit comprising a pair of supporting blocks, a pair of cylinders having shafts journaled at their ends in said blocks, means carried by the blocks for adjusting one cylinder with respect to the other, and gearing through which said cylinders may be turned, a make-ready stand having means for supporting said cylinder unit, and gearing adapted to be operatively connected to the gearing of the unit to turn the cylinders.

17. A printing press comprising a frame, a plurality of superposed cylinder units removably mounted in the frame, a second frame movably mounted in the press frame, means for detachably locking said second frame to the press frame in a position adjacent the cylinder units, and superposed inking mechanisms carried by said frame and adapted to be operatively connected to the cylinder units.

In testimony whereof, I hereunto affix my signature,

GEORGE L. FULK.
